US0D1099911S

(12) **United States Design Patent** (10) Patent No.: **US D1,099,911 S**
(45) Date of Patent: ** Oct. 28, 2025

(54) **DISPLAY SCREEN OR PORTION THEREOF WITH GRAPHICAL USER INTERFACE**

(71) Applicant: **Apple Inc.**, Cupertino, CA (US)

(72) Inventors: **Mani Amini**, San Jose, CA (US); **Alan C. Dye**, San Francisco, CA (US); **Aurelio Guzmán**, San Jose, CA (US); **Sascha Höhne**, Rellingen (DE); **Stephen O. Lemay**, Palo Alto, CA (US); **Alexander Harry Little**, Woodside, CA (US); **Wyatt R. Mitchell**, San Francisco, CA (US); **Christopher Wilson**, San Francisco, CA (US)

(73) Assignee: **Apple Inc.**, Cupertino, CA (US)

(**) Term: **15 Years**

(21) Appl. No.: **29/849,366**

(22) Filed: **Aug. 10, 2022**

Related U.S. Application Data

(63) Continuation of application No. 29/718,901, filed on Dec. 30, 2019, now Pat. No. Des. 960,916, which is a continuation of application No. 29/649,954, filed on Jun. 4, 2018, now Pat. No. Des. 872,129.

CLAIM

The ornamental design for a display screen or portion thereof with graphical user interface as shown and described.

DESCRIPTION

The sole FIGURE shows a display screen or portion thereof with graphical user interface showing our new design. The peripheral dashed broken lines illustrate a display screen or portion thereof, and form no part of the claimed design.

The text illustrated in broken lines forms no part of the claimed design.
